UNITED STATES PATENT OFFICE.

WILLIAM BROWN AND ALBERT WEBER, OF SAN FRANCISCO, CALIFORNIA.

BACKING-LUMBER FOR HALF-TONES.

No. 841,115.

Specification of Letters Patent.

Patented Jan. 15, 1907.

Application filed April 17, 1906. Serial No. 312,272.

To all whom it may concern:

Be it known that we, WILLIAM BROWN and ALBERT WEBER, citizens of the United States, residing in the city and county of San Francisco and State of California, have invented new and useful Improvements in Backing-Lumber for Half-Tones, of which the following is a specification.

Our invention relates to backing for half-tones, zincos, and the like.

The object of the present invention is to provide a cheap backing-lumber for half-tones, zincos, and the like which will not warp, which is maintained in a non-warping condition by means other than metal reinforces, and which may be cut up into any size block and trimmed as desired.

The invention consists of the parts and the construction and the combination of parts, as hereinafter more fully described and claimed, having reference to the accompanying drawings, in which—

Figure 1 is a perspective view of our improved backing-lumber, showing it with a half-tone tacked on. Fig. 2 is a perspective of a section of backing-lumber provided with screws, anchorages, and grooves. Fig. 3 is a perspective view of a section of backing-lumber provided with a backing-plate and a half-tone sweated to the backing-plate.

In carrying out our invention we take a board of suitable thickness and of any desired length and width. A represents such a board. By "board" we mean wood, pulp, or any like suitable and cheap equivalent. This board is mortised on both sides crosswise of the grain, with the mortises on one side alternating with those on the other and with the mortises preferably a little deeper than half the thickness of the board. Into these mortises are set the straight-grained wood strips 2, which are glued in or otherwise permanently secured in place, (except that preferably no tacks or nails are used,) and then the strips are planed off flush with the top and bottom surfaces of the board. This constitutes in its simplest form our lumber, which may be carried in stock in any desired quantity and in any desired size of boards, the latter to be cut up as needed into any desired size or shape of blocks for large, small, or medium half-tones and zincos.

The cheapest of woods may be used in the manufacture of this lumber. By inserting the cross-strips 2 on both sides of the board there is no tendency, as we have amply dem-

onstrated in practice, for the wood to warp either way. If one takes a plain piece of wood or ordinary wooden backing-block, even though it is of the hardest and most expensive of woods, and tacks a half-tone onto it, it is only a short time before the block becomes warped and buckles the half-tone. Also if the cross-strips 2 are secured only to one side of the board the unbraced side will soon show a tendency to curl at the edges or warp and cause trouble. By making the mortises deeper than half the thickness of the board, so that all the grains in the board are severed at frequent intervals, and employing corresponding cross-strips we find that it improves the non-warping qualities of the board.

The cross-strips on one side are arranged alternately and parallel with those on the other for the purpose of enabling a board to be cut up into smaller blocks, which will not warp either.

The half-tone *a* or zincos or other printing-plate may be secured direct to the block by tacks *b*, as shown in Fig. 1, or by sweating the plate onto the heads of screws *3*, which latter are screwed into the board or block, as in Fig. 2. In this case the board after being mortised and tenoned, as previously described, is studded with screws or like metal inserts at suitable intervals on one side, the screws being driven in flush with the top surface of the board and arranged in symmetrical order, so as not to interfere with the board being cut up into proper blocks. This construction may be used where it is desired to use our non-warping wood block with such means to secure a plate thereto as will permit the block and plate to be trimmed on all sides close up to the edge of the picture or other printing matter on the plate. Where the plate is tacked direct to the block there is always a narrow blank border left around the picture which is usually lost space.

In Fig. 3 is shown another modification of the invention in which our mortised and tenoned board may have a soft-metal plate *4*, about an eighth of an inch, more or less, in thickness, secured to its top surface by screws, nails, or other suitable means, and the half-tone *a* may be tacked or sweated to this plate. This also enables the lumber to be cut up into blocks and permits a block and plate to be trimmed.

It may be advisable under some conditions and with some kinds of woods to pro-

vide the top surface of the mortised and tenoned board with a series of transverse and longitudinal shallow and narrow grooves 5, which permit a circulation of air beneath the 5 plate and so operate to maintain both sides of the wooden block at the same temperature and subject to the same conditions of moisture and dryness. With the plain wood block and a plate secured direct to it the top 10 of the block beneath the plate often gets very hot and dried out, while the under side of the block absorbs moisture from the atmosphere. This is the cause or one of the causes of the block warping and the plate buckling. The 15 grooving of the block, as shown, tends to overcome this difficulty, and while it is not essential with our mortised and tenoned structure it is nevertheless advantageous.

Having thus described our invention, what 20 we claim, and desire to secure by Letters Patent, is—

1. A backing-lumber for half-tones comprising a board having transverse mortises on its two sides, tenons set into said mortises 25 flush with the surfaces of the board, said mortises and tenons arranged to permit the board to be cut into smaller sections having the same characteristics as the original board.

2. A non-warping backing-lumber for half- 30 tones, comprising a board having transverse mortises on its two sides, tenons set into said mortises flush with the surfaces of the board, screws set permanently into one side of said board flush with the surface thereof, said 35 screws, mortises and tenons arranged to per-

mit the board to be cut into sections having the same characteristics as the board itself.

3. A backing-lumber for half-tones comprising a board having transverse mortises on its two sides, and tenons set into said mortises flush with the board, said board having metal inserts at suitable intervals forming anchorages for the half-tones.

4. A non-warping backing-lumber for half-tones comprising a board having transverse 45 mortises on its two sides, and tenons set into said mortises flush with the board, said mortises on one side of the board arranged alternately with those on the opposite side of the board.

5. A non-warping backing-lumber for half-tones comprising a board having transverse mortises on its two sides, tenons set into said mortises flush with the board, said mortises on one side of the board arranged alternately 55 with those on the opposite side of the board, said mortises and tenons having a depth greater than half the thickness of the board, and said mortised and tenoned board having shallow and narrow grooves on the side which 60 is to support the half-tone.

In testimony whereof we have hereunto set our hands in presence of two subscribing witnesses.

WILLIAM BROWN.
ALBERT WEBER.
